UNITED STATES PATENT OFFICE

ALLAN J. CLINE, OF CHICAGO, ILLINOIS

DRIVING MECHANISM FOR PRINTING PRESSES

Application filed August 8, 1931. Serial No. 555,956.

This invention relates to printing presses and particularly to certain improvements in press drives.

In my Patent No. 1,734,077, issued November 5, 1929, there is shown and described a unit type press in which the separate units of the press, as well as the folders, are each driven from a separate motor. In said patent the individual drive motors are arranged with their armatures extending parallel to the spindles of the driven press cylinders, the armatures being connected to the respective cylinder spindles by means of a chain drive. The armature shafts of the individual motors are therein shown as being connected by means of suitable gearing to an equalizing shaft which extends along the side of the press, the several units being thus interconnected to maintain perfect synchronism between the various units of the press.

I have found that a more efficient arrangement of the individual drive motors may be obtained by placing the individual motors in axial alignment with one another since the several armature shafts may then be directly interconnected to equalize the speed of the separate press units without requiring the use of a gear connection between each motor armature and the equalizing shaft. With this arrangement of the motors I also dispense with the chain type of drive disclosed in my patent above referred to, the individual units, and the folders, being directly connected through suitable power take-off shafts with their respective drive motors.

The invention will be fully understood from the following detailed description, taken in connection with the accompanying drawing, wherein I have shown a preferred arrangement of the press drives.

Referring to the drawing:

Fig. 1 is a broken elevational view, partly in section, showing a portion of a unit press embodying the improved drive mechanism;

Fig. 2 is a detail section taken on line 2-2 of Fig. 1, the view illustrating a portion of the driving connection between one of the motor armature shafts and a power take-off shaft; and

Fig. 3 is a view similar to Fig. 2 showing

a modified type of gearing which may be used to connect the motor armature shaft with the take-off shaft leading to the press unit.

In conformity with the usual practice in unit type press construction, the individual printing units, and folders, are arranged in a continuous row and are mounted in the press frame of which the uprights 5 and top bar 6 are shown. Each of the printing units comprises a pair of printing couples, the first couple consisting of an impression cylinder 8 and a printing cylinder 9, and the second couple similarly consisting of an impression cylinder 11 and a printing cylinder 12.

It will be understood that the couples of each unit are interconnected by suitable gearing (not shown) whereby they are driven in unison with one another by means of power supplied to bevelled gear wheels 13 secured to the spindles which support the driven press cylinders. The web is drawn into the press from a web roll which is located below the press room floor 7. After passing through the printing unit the web is guided over suitable guide rollers 14, and thence passes to a folder 15 where the webs from the several units are reduced to page form. According to the usual practice, one side of the web is printed in the first couple of the unit and the other side is printed in the second couple of the unit, both sides of the page being thus printed in a single unit.

The folder 15 is shown more or less diagrammatically. One of the driven folder rollers is indicated at 16, the shaft 17 which supports said roller being connected by suitable gearing to a bevelled gear wheel 18 to which power is supplied by the drive system hereinafter described. The top rollers of the folder (not shown) are similarly arranged to be driven from a bevelled gear wheel 19.

Each of the printing units, as well as folder 15, is arranged to be driven from separate motors which, in the present embodiment, are positioned below the press room floor. The printing unit drive motors are indicated by the numeral 21 and the folder drive motor is indicated by the number 22. Each of these motors is hung by brackets 23 from the press room floor 7. Power is supplied directly to

the gear wheels 13 from their corresponding motors 21, the drive connection for each unit consisting of a vertically disposed shaft 25, the upper end of which carries a bevelled pinion 26 which meshes with bevelled gear wheel 13. The lower end of shaft 25 carries a worm wheel 27 which meshes with a worm gear 28, the latter being rigid on the armature shaft 29 of the motor 21. A clutch 31 is provided in each of the shafts 25 so that the separate printing units may be disconnected when it may not be desired to employ them in the combination of units employed for a particular run of the press.

15 Power is supplied to the folder 15 through gear wheels 18 and 19 from motor 22, the driving connection consisting of a vertically disposed take-off shaft 32 which carries bevelled pinions 33 and 34 which mesh, respectively, with gear wheels 18 and 19. Shaft 32 carries on its lower end a worm wheel which meshes with a worm gear 35 carried on the armature shaft 36 of motor 22. A clutch 37, interposed in shaft 32, allows the folder to be disconnected from motor 22.

From the foregoing it will be noted that each of the printing units, and the folder, are driven from separate motors in accordance with the general scheme outlined in Patent 30 1,734,077. The advantage of employing individual motors, as outlined in said patent, resides primarily in giving greater flexibility in the accommodation of the several printing units and the folders to particular runs, 35 and also in dispensing with the heavy power transmission equipment required when a single large motor is employed for driving several units.

As previously stated, one of the objects of 40 the present invention is to provide an improved arrangement for the individual drive motors. In said patent above referred to, the individual motors are positioned with their armature shafts parallel to the press 45 cylinders, a chain drive being employed to connect the motor with the driven press cylinder. Such an arrangement requires that each motor be provided with gear connections associating it with the equalizing shaft 50 of the system. It will be noted that according to my invention, the motors 21 and also the motor 22, are positioned in axial alignment with one another. With this arrangement of the motors, it is not necessary to 55 connect each one through a separate gear box to a common equalizing shaft. It is merely necessary to connect the motors together by means of shafting 38 which in effect is but a continuation of the armature shafts of the 60 motors. Since, however, shafting 38 is merely employed for equalizing purposes, it need not necessarily be of as heavy construction as the portions of the armature shafts lying between the motors and the power 65 take-off shafts 25 and 32. No great amount

of power is transmitted from one unit to the other by shafting 38, its function being merely to keep the several units synchronized. Clutches 39 are provided in shafting 38 to 70 allow the several units, and the folder, to be disconnected from one another.

While the aligned arrangement of the motors may be employed regardless of the particular location of the motors relative to the press, I prefer to locate the motors below 75 the press room floor as shown. When thus located the motors are completely out of the way and do not interfere with the work of the pressmen in the make-ready operations and in such operations as for example, attaching an auxiliary color unit to the press. With the motors located below the press room floor in the manner shown, I have found that it is particularly desirable to employ a worm 80 drive for connecting take-off shafts 25 and 32 with their respective armature shafts. The advantage in using a worm drive resides primarily in the fact that it permits of the 85 location of take-off shafts 25 and 32 close to the press frame. This is best illustrated in 90 Fig. 2. In this figure it will be noted that the columns 41, which support the press, are located in approximate alignment with the frame uprights 5. The great weight of the 95 press requires that a direct support of this nature be provided. By reason of this location of the press columns, it is necessary to position the motors some distance from the side of the press. The armature shaft of the motor must necessarily be displaced from the side of the press a distance at least half the width of the motor. However, by using the worm wheel 27 on the lower end of shaft 25, the distance the motor armature is offset from the side of the press is accounted for in the width of the gear. Hence, it is not necessary to bring shaft 25 very far from the press frame. The take-off shafts 25, as well as the folder take-off shaft 32, can thus 100 be located close to the press frame even though the construction of the press sub-structure may prevent the location of the motors with their center line in the same vertical plane as said shafts 25 and 32.

In Fig. 3, shaft 25 is shown connected to 105 armature shaft 29 through a pair of hypoid gears 42 and 43. The use of the hypoid gears also permits of the off-setting of armature shaft 29 from take-off shafts 25 and 32. While this arrangement may in some cases 110 be preferred over the worm gear drive, it is generally considered less desirable by reason of the fact that the power take-off shafts 115 cannot be located as close to the press frame as they can in the case where the worm drive is used as shown in Fig. 2. With the hypoid gears the maximum off-set between the take-off shafts and the armature shafts would be 120 about one-fifth of the pitch diameter of gear 42.

It will be understood that the press shown is merely intended to be illustrative of one arrangement of the unit type press to which the invention may be applied. Such variations in press construction, as for example, the provision of separate drives for each couple of a printing unit, are to be considered as fully within the scope of the invention.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. A unit type press comprising a series of associated printing units, individual motors for driving each of said units, said motors being positioned with their armature shafts in axial alignment with one another, and connecting means extending between said armature shafts for equalizing the speed of the motors.

2. A unit type press comprising a series of associated printing units, folders arranged at intervals in the series, an individual motor for driving each printing unit and each folder, said motors being positioned with their armature shafts in axial alignment with one another, and connecting means extending between said armature shafts for equalizing the speed of the motors.

3. A unit type press comprising a series of associated printing units, individual motors for driving each of said units, said motors being positioned with their armature shafts in axial alignment with one another, connecting means extending between said armature shafts for equalizing the speed of the motors, and a power transmission shaft connecting each motor with its associated printing unit.

4. A unit type press comprising a series of associated printing units, individual motors for driving each of said units, said motors being positioned with their armature shafts in axial alignment with one another, connecting means extending between said armature shafts for equalizing the speed of the motors, a power transmission shaft connecting each motor with its associated printing unit, and coupling means in said transmission shaft for disconnecting the unit from its drive motor.

5. A unit type press comprising a series of associated printing units, individual motors for driving each of said units, said motors being disposed below and to one side of the press frame and positioned with their armature shafts in axial alignment with one another, connecting means extending between said armature shafts for equalizing the speed of the motors, and a power transmission shaft extending between the armature shaft of each motor and its associated printing unit, said transmission shafts being disposed in a plane which is offset from the plane of the motor armature shafts.

6. A unit type press comprising a series of associated printing units, individual motors for driving each of said units, said motors being disposed below and to one side of the press frame and positioned with their armature shafts in axial alignment with one another, connecting means extending between said armature shafts for equalizing the speed of the motors, and power transmission means connecting each motor with its associated printing unit comprising a shaft extending between the motor armature shaft and the driven press cylinder, and a worm gear drive connection between said shaft and the motor armature shaft.

7. A unit type press comprising a series of associated printing units, individual motors for driving each of said units, said motors being disposed below and to one side of the press frame and positioned with their armature shafts in axial alignment with one another, connecting means extending between said armature shafts for equalizing the speed of the motors, and power transmission means connecting each motor with its associated printing unit comprising a shaft extending between the motor armature shaft and the driven press cylinder, and a hypoid gear drive connection between said shaft and the motor armature shaft.

In witness whereof, I hereunto subscribe my name to this specification.

ALLAN J. CLINE.
